US0D1016120S

(12) **United States Design Patent** (10) **Patent No.:** **US D1,016,120 S**
(45) **Date of Patent:** **** Feb. 27, 2024**

(54) **CAMERA**

(71) Applicant: **Google LLC**, Mountain View, CA (US)

(72) Inventors: **Moonchul Kim**, Santa Clara, CA (US); **Sung Bai**, San Jose, CA (US); **Maj Isabelle Olsson**, Sunnyvale, CA (US); **Étienne Bérubé**, San Francisco, CA (US)

(73) Assignee: **GOOGLE LLC**, Mountain View, CA (US)

(**) Term: **15 Years**

(21) Appl. No.: **29/910,556**

(22) Filed: **Aug. 22, 2023**

Related U.S. Application Data

(62) Division of application No. 29/799,861, filed on Jul. 16, 2021.

(74) *Attorney, Agent, or Firm* — LEASON ELLIS LLP

CLAIM

The ornamental design for a camera, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front perspective view of a camera showing our new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof; and,

FIG. 7 is a bottom plan view thereof.

1 Claim, 7 Drawing Sheets
(7 of 7 Drawing Sheet(s) Filed in Color)
